UNITED STATES PATENT OFFICE

165,369

LACE HOLDER

Bruno Fortuna, North Bergen, N. J.

Application November 3, 1949, Serial No. 5,846

Term of patent 14 years

(Cl. D80—5)

To all whom it may concern:

Be it known that I, Bruno Fortuna, a citizen of the United States, of North Bergen, New Jersey, have invented a new, original, and ornamental Design for a Lace Holder, of which the following is a specification, reference being had to the accompanying drawing, forming a part thereof, in which:

Fig. 1 is a front view of a lace holder, showing my new design.

Fig. 2 is a side edge view thereof.

Fig. 3 is an enlarged section on the line 3—3 of Fig. 1.

Fig. 4 is an enlarged section on the line 4—4 of Fig. 1.

Fig. 5 is an enlarged section on the line 5—5 of Fig. 1.

The back of the lace holder is identical with the front.

I claim:

The ornamental design for a lace holder, as shown and described.

BRUNO FORTUNA.
